ROCKET LAUNCHER

Earl C. Walker, Altadena, Calif., assignor to the
United States of America as represented by the
Secretary of the Navy

Application July 18, 1945, Serial No. 605,651

3 Claims. (Cl. 89—1.7)

1

This invention relates to rocket launchers and more particularly to a launcher of novel construction in which a plurality of rockets is fed automatically in succession into firing position on a launcher track in response to successive firing of rockets from the track.

One object of the invention resides in the provision of an automatic launcher having an escapement mechanism for controlling the feeding of rockets to a launcher track and which serves as a support and guide for the rocket being fired.

Another object is to provide a rocket launcher of the character described, in which the escapement mechanism is so arranged that the weight of the rounds of rockets in the storage space or magazine does not materially effect the engaging pressure between the round on the launcher track and the guide means for such round, so that the number of rounds in the magazine has no appreciable effect on the discharge of rockets from the launcher track.

A further object is to provide an automatic rocket launcher which is compact and occupies only slightly more space than the rockets which it carries.

Still another object is to provide an automatic rocket launcher which may be tilted to different angles of elevation without affecting its operation.

An additional object is to provide a rocket launcher which is a further development of the launcher disclosed in a co-pending application of Lorenzo A. Roberts Serial No. 610,655, filed August 13, 1945.

Another object is to provide an automatic rocket launcher particularly adapted for launching rotating rockets of the type disclosed in a co-pending application of C. E. Weinland, Serial No. 564,337, filed November 20, 1944, but which may be used for non-rotating rockets, the essential difference being that the launcher rail or track is longer when the launcher is used for non-rotating rockets.

Another object is to provide a rocket launcher in which rounds of rockets are automatically fed by gravity into firing position on a launcher track from a magazine located above the rack.

Another object is to provide a rocket launcher which may be made to operate automatically or semi-automatically, as desired; that is, which is operable selectively to fire each round as fast as it moves into launching position, or to require closing of a firing circuit, or the like, by the operating crew each time it is desired to fire a round.

These and other objects of the invention may

2

be better understood by reference to the accompanying drawings, in which

Fig. 1 is a side elevational view of one form of the new launcher;

5 Fig. 2 is a plan view of the launcher shown in Fig. 1;

Fig. 3 is a side view in detail of the escapement mechanism for controlling feeding of the rockets to the launching track, parts of the mechanism 10 being broken away for illustrative purposes;

Fig. 4 is a rear end view of the escapement mechanism shown in Fig. 3;

Fig. 5 is a rear end view of the launcher shown in Figs. 1 and 2;

15 Fig. 6 is a front view of the launcher shown in Figs. 1 and 2;

Fig. 7 is a front view of a modified form of the new launcher, and

20 Fig. 8 is a detail vertical section on the line 8—8 of Fig. 7.

Referring to the drawings, the launcher shown in Figs. 1 to 6, inclusive, comprises a base frame 10 having cross members 12 and longitudinal members 13 made of angle iron. The rear cross member 12 is provided with a pair of laterally extending mounting lugs 14 adapted to fit in suitable fixtures (not shown) which permit movement of the launcher frame 10 round the axis defined by the mounting lugs. Intermediate the 25 ends of the longitudinal members 13 is a transversely extending mounting member 15 in the form of an inverted channel and which is adapted to receive a fixture 15a adjustable in any suitable manner to elevate or depress the launcher. If desired, the mounting arrangement used for the 30 rocket launcher disclosed in said co-pending application, Serial No. 610,655 may be used and the launcher herein disclosed and the aforementioned launcher may be interchangeable.

40 At the rear end portion of the base frame 10 is a pair of prependicular posts 16. A second pair of perpendicular posts 17 is mounted on the frame over the mounting channel 15, that is, intermediate the ends of the frame. The front end portion of the frame 10 is provided with upwardly 45 extending bracing posts 18 which curve rearwardly and join the intermediate posts 17. At their upper ends the intermediate posts 17 are joined by a cross member 19. It will be observed that the upper portion of one of the posts of each pair 16, 17 and 18 is located a substantial distance inwardly from the corresponding side of the frame 10, while the lower portion of each of these 50 posts is offset outwardly toward the side of the

55 posts is offset outwardly toward the side of the

frame, as shown at 16a, 17a and 18a respectively, to accommodate an escapement mechanism to be described.

The inner sides of the offset post portions 16a and 18a are provided with escapement mounting blocks 21 and 21a respectively, for supporting bearings 22 between which an escapement mechanism 23 is mounted. A journal member 24 terminating at its ends in journal pins or trunnions 24a (Fig. 3) is mounted between the front and rear bearings 22 and extends parallel to the frame 10. Secured to the journal member 24 adjacent each bearing 22 is an end yoke 26 (Fig. 4). The lower arms of the end yokes 26 are joined by a longitudinally extending guide rod 27.

The cross members 12 of the base frame support a bottom guide rail 28 intermediate the longitudinal members 13, while the posts 16, 17 and 18 opposite the offset post portions support a side guide rail 29. The guide rails 28 and 29, together with the guide rod 27, define points on a common circle which are approximately 120 degrees apart and form a rocket launching track. More particularly, the rocket (illustrated in outline at A in Figs. 5 and 6) is supported along the bottom on the guide rail 28 when the rocket is in firing position, and along its sides by the guide rod 27 and side rail 29. The rocket A may be of any desired construction, such as that disclosed in a co-pending application of C. E. Weinland, Serial No. 564,337, filed November 20, 1944.

Above the guide rail 29, the forward and intermediate posts 16 and 17 are connected by a tubular stop bar 30. The end yokes 26 of the escapement mechanism have upwardly and inwardly extending arms between which a restraining roller 31 is journaled. The arrangement of the yokes 26, which carry the guide rod 27 and restraining roller 31, is such that when the guide rod 27 bears against the side of a rocket resting between the rails 28 and 29, the space between the restraining roller 31 and the stop bar 30 is insufficient to admit an overlying rocket B into position on the lowermost rocket, as shown in Figs. 5 and 6.

The pairs of posts 16, 17 and 18 define the sides of a vertical slot extending the length of the guide rails, the slot forming a rocket magazine. The two rear posts 16 are connected by a magazine end channel 32 adapted to receive the rear end portions of a plurality of rocket rounds stacked one above the other in the magazine slot. The end channel 32 terminates at its lower end above and clear of a rocket resting in the launching track defined by guide rod 27 and guide rails 28 and 29. However, the channel 32 has a central, internal rib 33 which projects below the lower end of the channel so that the rib is engaged by the rear end of a rocket in the launching track, thereby preventing rearward displacement of the rocket in the track when the launcher is elevated.

As shown in Figs. 3, 4, 5 and 6, the escapement mechanism 23 is provided intermediate its ends with a lever 34 connected to the journal member 24, the lower or free end of the lever being forked to receive the guide rod 27. The lever 34 has a laterally extending arm 34a to which the upper end of a tension spring 35 is connected, the lower end of the spring being secured to the underlying longitudinal member 13. Thus, the spring 35 pulls arm 34a downward to urge guide rod 27 against the rocket A in the launching track, and to turn the escapement mechanism clockwise (Fig. 6) when the rocket is fired, thereby moving the restraining roller 31 outwardly a sufficient distance to permit the next rocket B in

the magazine to fall down on the launcher track into firing position.

In the operation of the launcher, the rockets are loaded into the top of the magazine through the open space between the upright standards 17 and the rear channel member 32, by inserting the noses of the rockets between the uprights 17 and then moving the rockets back so that their tail ends are in contact with the skid rail 33 within the rear channel 32, the first rocket being lowered to the guide rails 28 and 29 of the firing chamber, as shown in Figures 5 and 6. The second rocket B rests clear of the first or lowermost rocket and is supported by the restraining roller 31 and the stop bar 30, while the other rockets tiered in the magazine are supported by the second rocket.

As indicated heretofore, the lowermost rocket, which is on the rail 28, is engaged along one side by the guide rod 27 of the escapement mechanism and holds this rod outwardly against the tension of spring 35. As a result, the escapement roller 31 is held inwardly in the magazine so that the clearance between this roller and the stop bar 30 is smaller than the rocket diameter, whereby the second rocket B and those above it are supported jointly by the stop bar 30 and the roller 31.

When the lowermost rocket A is fired, as by electrically igniting its propellant charge, it moves forwardly along the launcher base and is guided in its initial forward movement by the guide rod 27 and the rails 28 and 29. When the rocket leaves the launcher, the guide rod 27 is no longer engaged and is free to move inwardly under the action of spring 35, which turns the escapement mechanism 23 in a counterclockwise direction, as seen in Fig. 5. Consequently, the roller 31 moves outwardly and permits the second rocket, which previously rested thereon, to fall down on the guide rail 28. During this downward movement of the second rocket, it engages the guide rod 27 and displaces the latter outwardly so as to move roller 31 back to its innermost position against the action of spring 35. Thus, the roller 31 is now in position to engage the third rocket and, in combination with stop bar 30, prevent the third rocket from dropping into the launching track. This action continues until all the rockets have been fired.

Preferably, the rockets used in the new launcher whether of the rotating type disclosed in said co-pending application, Serial No. 564,337, or of the non-rotating type such as that disclosed in a co-pending application of C. C. Lauritsen, Serial No. 481,644, filed April 2, 1943, now Patent Number 2,464,181, are electrically ignited. More particularly, as shown in said co-pending applications, each rocket is provided at its rear end portion with an insulated contact ring and also a grounded contact ring. The rockets, in dropping to the guide rail 28, are engaged on their insulated and grounded contact rings by respective insulated and grounded contacts (not shown) on the launcher. The contact arrangement is not illustrated herein for the reason that it forms no part of the present invention. However, the contact arrangement similar to that disclosed in a co-pending application of C. C. Lauritsen, Serial No. 481,645, filed April 2, 1943, now Patent Number 2,469,350 may be used. It will be understood that the electrical contacts are suitably connected with a firing circuit which, if continuously energized, automatically fires the rockets as they fall to the guide rails 28 and 29. If, however, the firing circuit is arranged so that

it can be energized momentarily, each rocket may be fired individually.

In the construction illustrated, the rocket launcher is not appreciably larger than the rockets which it fires, and the escapement mechanism, or at least the guide rod 27, is equal in length to the guide rails 28 and 29 so that the rocket clears all rails simultaneously. This arrangement is satisfactory for use with multiple jet rotating rockets. If it is desired to use the launcher for non-rotating rockets, such as barrage rockets, it is desirable to lengthen the launcher track; otherwise, the construction may be the same.

It will be observed that the framework 10 is open and that the track comprising guide rod 27 and guide rails 28, 29 permits ready escape of the rocket blast so that there is no appreciable reaction on the launcher. Accordingly, a very light mounting is sufficient to hold the launcher in its original position during firing of all the rounds. The launcher may be adjusted in elevation to different firing positions by means of the mounting fixture 15a which serves to tilt the frame 19 on the mounting lugs 14.

By reason of the oscillating escapement mechanism 23 for controlling the feeding of the rockets to the launcher track, a substantially uniform pressure is maintained on each rocket in the launcher track, regardless of the number of overlying rockets in the magazine, and this pressure may be controlled or varied as desired by adjusting the tension of spring 35.

Referring now to Fig. 7, the launcher there shown comprises a base plate 40 which may be made of sheet stock in the form of an inverted channel, the channel 40 being closed at its ends by end plates 42 inserted flush with said ends (Fig. 8) and welded in position. Mounted on top of the base plate 40 is a rail 43 occupying about half the width of the base plate. The rail is likewise made of sheet stock and has a pair of longitudinally extending side flanges 44 in the form of open loops.

Brackets 45 that form the near and far ends of a rocket magazine are suitably secured to the base plate 40 at one side and a portion of the top as shown. The magazine-end brackets 45 project upwardly and outwardly from the base plate and in parallel relation to each other the upper edges of the brackets being tangent to the upper edge of the inner flange 44 of the rail. Mounted on the end brackets 45 at the front and rear end portions of the base plate are guides 46 which engage and guide the front and rear end portions respectively, of rockets A, B, etc., indicated by dotted outline in Fig. 7. The arrangement of the end brackets 45 and their guides 46 is such that the rockets tend to roll into the rail member 43.

At the front and rear ends of the base plate 40 are escapement support arms 47. The lower ends of the arms are secured to the end plates 42 at one side of the rail member 43, whence they extend upwardly from the base plate 40 and then curve inwardly over rail 43. An escapement mechanism 48 is mounted between the support arms 47 and comprises a pair of rods 49 and 50 extending parallel to base plate 40 and joined at their ends and intermediate their ends by arcuately shaped connecting members 51. Bearing blocks 52 are welded to the two end connecting members 51 and have central openings for receiving journal lugs 53 on the inner sides of the two support arms 47. The journal lugs 53

are preferably flattened, and the bearing openings communicate with slots 54 so located that in one position of the escapement mechanism 48 it may be entirely removed from or mounted on the support arms. The location of the axis of rotation of the escapement mechanism 48 is above a plane common to the two rods 49 and 50.

The rod 49 is located so that it engages the upper surface of a rocket A resting in the track 10 43 between flanges 44. When the rod 49 is thus engaged by a rocket in the track, it holds the rod 50 in the path of the lowermost rocket B resting on the side brackets 45. That is, the rod 50 is held in a lowered position so that the distance between this rod and the upper edge of the side bracket 45 is insufficient to allow a rocket to move from the bracket downwardly into the launcher track. However, when the rocket A in the track 43 is fired, the rod 49 is disengaged 20 and allows the rod 50 to move upwardly about the trunnions 53, whereby the lowermost rocket on the side brackets 45 rolls downward along the brackets and into the launcher track. As the rocket moves into the launcher track, it engages and elevates the rod 49 so that rod 50 is again depressed to its lowermost position into the path of the next rocket on the side brackets, thereby effectively preventing this rocket from moving down into the launcher track. This operation is repeated until all of the rockets on the side brackets 45 have been launched.

It will be understood that the launcher shown in Fig. 7 is adapted to fire rockets of the type described in connection with the launcher illustrated in Figs. 1 through 6. That is, the launcher track 43 is provided with grounded and insulated contacts (not shown) engageable with the usual grounded and insulated tail rings, respectively, on the rocket when the latter is in the track. 35 The guides 46 are so located that each rocket is caused to roll into the track with the grounded and insulated tail rings engaging the corresponding contacts on the track. A portion of the track 40 43 near the rear end thereof may be cut away so that the insulated tail ring on the rocket engages only the live contact on the track. It is to be understood that the insulated and grounded contacts on the track are connected across a current source (not shown) by suitable wiring 45 which may include a firing switch. Thus, when the firing switch is held closed, the rockets will be fired in quick succession from the track 43 until the supply of rockets on the side brackets 45 is exhausted. Alternatively, the firing switch 50 may be alternately closed and opened to fire successive rockets at any desired time interval. In either case, the oscillating escapement mechanism 48 serves to control the discharge of the rockets from side brackets 45 into the launcher 55 track and prevents the adjacent rocket on the side bracket from interfering with the firing of a rocket in the track. It will be observed that the rod 49 acts as a guide for the rocket being fired from the track and maintains a substantially uniform pressure on this rocket regardless of the number of rockets on the side brackets 45.

The base plate 40 may be provided with suitable fittings (not shown) so that it may be mounted on the tripod of a machine gun, or the base plate may be mounted on other suitable supports. If desired, additional rockets may be loaded into the outer side of the magazine, defined by the side brackets 45 and guides 46, during firing of the rockets from the launcher track, so that the firing may be continuous.

7
I claim:

1. A rocket launcher comprising a framework having a base and posts on opposite sides of the base to define a vertical magazine slot for receiving a stack of rockets, a bottom guide rail on said base and defining the lower extremity of said slot, a side guide rail on said posts at one side of the slot, a stop rail above the guide rail and mounted on the posts, and an escapement mechanism mounted on said posts on the opposite side of the slot from said side guide rail, the escapement mechanism including a pair of rods and means for mounting the rods for oscillating about a common center, one of the rods being engageable with a rocket resting against said bottom and side guide rail to form therewith a track for guiding the rocket, the other of said rods cooperating with said stop rail to restrain downward movement of rockets stacked in said slot while a rocket is in the track.

2. A construction as set forth in claim 1, in which the escapement mechanism and said guide rails are coextensive in length.

3. A rocket launcher comprising a base; upright posts on the base defining a magazine slot for receiving a stack of rockets above the base, a guide rail on the base adapted to be engageable with the bottom of a rocket from the magazine slot, a guide rail on the posts engageable with one side of a rocket on said bottom guide rail, a stop rail mounted above the side rail, an escapement mechanism at the side of the magazine slot opposite said side and stop rails and

5 having a rod engageable with the other side of a rocket on said bottom guide rail, whereby the rod and guide rails form a launching track, the escapement mechanism also having a restraining bar co-acting with said stop bar to secure overlying rockets in the magazine slot against movement into said launching track, and biasing means normally urging the restraining bar outwardly into position for admitting a rocket from the magazine slot into the launching track, said rod being engageable by a rocket moving into the launching track to displace the restraining bar inwardly into its rocket restraining position against the action of said biasing means.
